LENS HOUSING FOR AN AUTOMOBILE

Melvin C. Mawhinney, Southfield Township, Oakland County, Mich., assignor to Chrysler Corporation, Highland Park, Mich., a corporation of Delaware

Application September 7, 1951, Serial No. 16,557

Term of patent 7 years

(Cl. D48—32)

To all whom it may concern:

Be it known that I, Melvin C. Mawhinney, a citizen of the United States, residing in Southfield Township, county of Oakland, and State of Michigan, have invented a new, original, and ornamental Design for a Lens Housing for an Automobile, of which the following is a specification, reference being had to the accompanying drawing, forming part thereof, in which:

Fig. 1 is a front elevational view of a lens housing for an automobile showing my novel design;

Fig. 2 is a top plan view thereof; and

Figs. 3, 4 and 5 are sectional views taken on the lines 3—3, 4—4 and 5—5 of Fig. 1.

I claim:

The ornamental design for a lens housing for an automobile, substantially as shown.

MELVIN C. MAWHINNEY.
